UNITED STATES PATENT OFFICE.

ALBERT B. SCHOFIELD, OF NEW YORK, N. Y.

DESIGN FOR A MEMBER FOR WIRE-CUTTERS.

SPECIFICATION forming part of Design No. 31,862, dated November 21, 1899.

Application filed June 7, 1899. Serial No. 719,723. Term of patent 14 years.

To all whom it may concern:

Be it known that I, ALBERT B. SCHOFIELD, a citizen of the United States, and a resident of New York, in the county of Kings and State 5 of New York, have invented and produced a new and original Design for a Member for Wire-Cutters, of which the following is a specification.

The leading feature of my design consists 10 in a member of a wire-cutter presenting in side elevation a rounded disk having a short leg or branch extended from its periphery and provided with a central perforation, a perforation at or near the end of the projecting leg or branch, and with serrations at intervals in its periphery.

In the accompanying drawings, Figure 1 represents the member in side elevation, and Fig. 2 represents the member in edge elevation.

A represents the rounded head; a , the leg or branch projecting from its periphery; a' , the perforation at the center of the head; a^2 , the perforation at or near the end of the leg or branch, and a^3 one of the serrations in the 25 periphery of the member.

What I claim is—

The design for the member of a wire-cutter, substantially as herein shown and described.

In testimony that I claim the foregoing as my invention I have signed my name, in presence of two witnesses, this 4th day of June, 1899.

30

ALBERT B. SCHOFIELD.
